UNITED STATES PATENT OFFICE.

HENRY A. WAHLERT, OF ST. LOUIS, MISSOURI, ASSIGNOR TO THE AMERICAN BRAKE COMPANY, OF SAME PLACE.

LOCOMOTIVE-BRAKE.

SPECIFICATION forming part of Letters Patent No. 392,242, dated November 6, 1888.

Application filed August 21, 1888. Serial No. 283,320. (No model.)

To all whom it may concern:

Be it known that I, HENRY A. WAHLERT, a citizen of the United States, residing at St. Louis, in the State of Missouri, have invented 5 certain new and useful Improvements in Locomotive-Brakes; and I hereby declare the following to be a full, clear, and exact description of the same, reference being had to the accompanying drawings, wherein—

10 Figure 1 is a side elevation of a driver-brake embodying my invention. Fig. 2 is a plan view showing the brake as applied to the wheels of one side. Fig. 3 is a vertical section of Fig. 2 on the line $x-x$, looking in the direction of the full-line arrow. Fig. 4 is a 15 similar section on the line $y-y$, looking in the same direction; and Fig. 5 is an enlarged view similar to Fig. 2, parts being broken away.

Like letters refer to like parts wherever they 20 occur.

My present invention relates to the construction of that class of locomotive driver-brakes wherein the brake-shoes are applied to both sides of the wheels, usually termed "squeeze-brakes," and has for its object the production 25 of a simple and efficient combination of floating levers and pull-rods for use with a horizontal cylinder, and which will apply the power uniformly to both sides of the wheels.

30 To this end it consists, mainly, in the combination, with a cylinder having two pistons, of two floating or equalizing levers, a link or fulcrum rod for connecting the same, and pull-rods for actuating the outer shoes or the brake-beams thereof.

I will now proceed to describe my invention more fully, so that others skilled in the art to which it appertains may apply the same.

In the drawings, A indicates the locomotive-frame; B, the driver-wheels; C, a bracket attached to the frame for the support of the cylinder; D, a cylinder having the usual steam-pipe leading from port S to the engineer's valve (not shown) and provided with two oppositely-moving pistons, d , and push-bars $e-e$, all of which may be of any approved or well-known construction.

E indicates brake-heads suspended by hang-

ers F from the frame A between the wheels and provided with suitable shoes.

G G indicate two floating levers, one end of each pivoted to the corresponding brake-head E, as at f, and to the push-bar or piston in the corresponding end of cylinder D, as at g, while the opposite ends of said floating levers are 55 connected by pull-rods I I with suspended 55 brake-heads K K on the outer side of the wheels or to the transverse brake-beams L, which carry said brake-heads K K.

The floating levers G G are connected at 60 suitable points between their extremities by a fulcrum-rod, M, and the pull-rods I I may be supported by hooks N, secured to the frame A at suitable intervals.

The devices, being of the character described, 65 will operate as follows: When steam is given to cylinder D, the outward movement of pistons d will through appropriate push-bars $e-e$ force out the brake-heads E, and with them the attached ends of the floating levers G, and as 70 said levers cannot separate at their mid-length, because of the fulcrum-rod M, their opposite ends must move toward each other, exerting a corresponding pulling force on the pull-rods I I, which brings the outer brake-heads, K K, 75 against the drivers, so that both inner and outer brake-shoes are applied to the wheels with uniform and equal power.

Having thus described the nature and operation of my invention, what I claim, and desire to secure by Letters Patent, is—

In a locomotive-brake, the combination, with a cylinder having two pistons, of two floating levers, each connected at or near one end to its respective piston, and at or near the other 85 end to a pull-rod, and a fulcrum-rod which connects the floating levers at points between their extremities, substantially as and for the purposes specified.

In testimony whereof I hereunto affix my 90 signature, in the presence of two witnesses, this 26th day of July, 1888.

HENRY A. WAHLERT.

Witnesses:

JOHN C. H. STEVENSON,
JNO. R. WILLIAMS.
